[57] CLAIM

The ornamental design for a multi-compartment bait box, as shown and described.

DESCRIPTION

FIG. 1 is a top, front and right side perspective view of a multi-compartment bait box, with lid in the open position, showing my new design;

FIG. 2 is a right side elevational view, the left side being a mirror image thereof;

FIG. 3 is a rear elevational view thereof; and,

FIG. 4 is a top, front and right side perspective view with the lid in closed position. The bottom surface is plain and unadorned.

FIG. 1

FIG. 2

FIG. 3**FIG. 4**
